UNITED STATES PATENT OFFICE.

WILLIAM T. HENSLEY, OF INDIANAPOLIS, INDIANA.

PULLEY.

Application filed January 2, 1923, Serial No. 610,175. Renewed May 16, 1927.

This invention relates to the manufacture of pulleys, and more particularly to those constructed from plates of suitable material, such as layers of strawboard or similar material alternating with metal plates, so that the edges of the fibrous material are presented at the surface of the pulley, thereby forming a desirable, frictional, tractive surface for a belt or other power transmission device.

It will be seen that this is an improvement on the construction shown in prior application No. 550,001, filed April 6, 1922 for improvement in pulleys.

It is an object of the invention to provide a balanced, symmetrical, laminated pulley of the type shown in my prior application Serial No. 550,001, filed April 6, 1922, for an improvement in pulleys, in which the laminated material is more dense at the inner portion than upon the outer surface, thus providing a relatively soft and maximum frictional surface for engagement with a belt or other power transmission device, and a relatively dense, inner portion having a maximum mechanical strength for engagement with a shaft.

More particularly, it is an object of the present invention to provide a strong, rigid, and yet relatively light, core structure in which the fibrous laminae are tightly clamped together and this without the use of securing means other than the rivets provided to hold the end plates together.

A further object of the invention is to provide a pulley which is adapted to receive end plates which may be recessed, as well as those of the flat type.

These and other objects of the invention will be apparent from the following description and annexed drawings, in which—

Figure 1 is a side elevation of a pulley embodying the principles of the invention, showing one end portion thereof in vertical longitudinal section to illustrate the method of combining the layers of strawboard or other fibrous material with the metal plates.

Figure 2 is an end elevation of the said pulley.

Figure 3 is a transverse section on line 3—3 in Figure 1.

Figure 4 is a face view of one of the metal plates.

Figure 5 is an edge view of said plate.

Figure 6 is a face view of one of the metal rivet bars employed for tying the con-

struction together after the compression thereof in the desired manner.

Figure 7 is an edge view of said rivet plate.

As shown in the drawings, the pulley comprises a plurality of laminae 1 of fibrous material, such as strawboard, paper, or other suitable material, alternating with the relatively hard plates 2, preferably of metal, so that when fibrous layers have been clamped and compressed between the plates the center 7 of the pulley will be more dense than the outer portion of the pulley. The plates 2 are smaller in diameter than the strawboard layers, and the strawboard material between the plates is compressed with a relatively large pressure, thus substantially increasing the density of the fibrous material to form a relatively hard, dense central portion adjacent the center 7. The outer portion of the pulley, however, is preferably not compressed sufficiently to materially increase its density so that it will present a relatively soft, frictional surface for power transmission.

The laminae of the pulley may consist of any suitable fibrous material, such as strawboard and the like, which is secured together and permanently held by any suitable means, such as rivets, as more fully described hereinafter.

The plates 2 are provided with notches or apertures 4, through which the rivet bars 3 may be passed. These are symmetrically arranged around the center of the pulley so that a balanced structure is provided. Furthermore, the rivet bars assist in binding the pulley together and with the metal plates 2, which have a relatively large surface engagement with the inner portions of the fibrous laminae, assist in transmitting the torque to the pulley or to the shaft, depending upon whether the pulley is driven by the shaft or drives the shaft.

The rivets 3 are preferably shouldered, as at 3^a, to provide reduced outer portions 3^b. The end plates, as shown, are preferably apertured to receive only the reduced portions 3^b of the rivets so that when the end plates are mounted on the assembly and placed in a press the shoulders 3^a will tend to limit the movement toward each other of the end plates and the portions 3^b may be headed over or expanded to tightly hold the end plates. By this means it is possible to control the widths of faces of the pulleys by

the length of the rivets as end plates are seated against the rivet shoulders 3^a. The notches or apertures 4 of the plates 2 are preferably of polygonal shape and the rivets 5 are similarly shaped to engage them. Due to this construction and also to the fact that the end plates are rigidly held against movement relative to the rivets by the shoulders 3^a of the rivets and the rivet heads, a skeleton 10 frame is produced which has considerable strength in itself due to the fact that the structure is rigid against endwise movement and against torsional movement, and this is true even in the absence of fibrous material, 15 which of course when present strengthens the structure.

The end plates may be countersunk or dished, if desired, and if sufficiently countersunk, it may be necessary to provide additional filler rings or laminæ 1^a, as indicated in Fig. 1.

The end plates 5 and the metal plates 2 may obviously be perforated when formed with a central aperture 8 of the proper size, 25 and also the end plates may be formed with notches 26 and the plates 2 with notches 9. When assembled and permanently secured together, it will thus be seen that a central bore 7 with a continuous key seat 27 is provided.

It is obvious, however, that the end plates 5 and the plates 2 may be formed with a relatively small central aperture which can be subsequently bored to the size desired and 35 can have a key seat subsequently formed therein.

Threaded apertures 25 may be provided for the set screws 6, the apertures 25 preferably passing through a rivet bar in order 40 that the threads may be formed in a substantial thickness of solid metal. It will, however, be noticed that when the metal plates are sufficiently close together, as shown in Fig. 1, threads are actually formed 45 throughout the radial length of a plurality of these plates, so that good metal threads are formed for a considerable length.

In the manufacture of my pulleys, fibrous units, either of polygonal or circular shape, 50 and metal units, such as shown in Fig. 4, are fabricated in any suitable manner from strips or sheets. The metal plates are preferably polygonal or non-circular, so that they will have no tendency to move relative to the fibrous material. In case fibrous units 55 of polygonal shape are used, the outer portions are subsequently trimmed to the desired contour.

In order to make my pulley, the paper or 60 fibrous laminæ and metal plates may be punched and assembled on any receiving device, ready for the reception of the end plates and rivets. After the end plates are applied and the rivets inserted, the assembly is 65 pressed with a relatively great pressure, such

as 4 or more tons per square inch. The inner portions of the fibrous laminæ are, therefore, compressed between the metal plates until the density of the fibrous material is substantially increased, thus forming 70 a relatively hard, dense central portion serving as a core, the fibrous part of which is integral with the fibrous material forming the outer portion of the pulley. The portion of the fibrous laminæ adjacent the outside surface is slightly pressed to give it a permanent set and yet it presents a relatively soft frictional surface. 75

During the assembling of the layers of fibrous material, or at any time, the strawboard may be treated with adhesive or any other liquid which will produce the desired effect, but this is preferably done by means of a waterproof binder, such as casein glue or any similar adhesive. The fibrous mass 80 with the waterproof glue or other adhesive therein may, while under compression, be dried in any suitable manner, as in an oven, and any shrinkage that may occur during the drying operation may be taken up by repressing and re-riveting in the press. Preferably, the grain of the strawboard runs in one direction in certain layers and at an angle thereto in other layers, so that the 85 grains will cross and the end grain of the 90 strawboard laminæ will be disposed around the circumference of the pulley, thus improving the strength of the pulley and the durability of the outer surface or face of the 95 pulley. At this time there is practically no 100 longitudinal strain on the rivets because the fibrous material has set or shrunk so that it does not have a tendency to expand or come apart.

While I have shown in the drawing, 105 blanks having perforations to receive four rivet bars, any desired number of rivet bars can be used but they should be symmetrical- 110 ly arranged so that a balanced pulley will be produced.

It is also obvious that in trimming the finished pulley the surface may be formed truly cylindrical or be formed with a crowned surface (not shown), as is common 115 in this art.

It will thus be seen that by compressing the inner portions of the fibrous laminæ between hard or metal plates of less radial dimension, I have produced a laminated pulley 120 which has its density considerably increased at the inner portion, so that it has a maximum mechanical strength for engagement with a shaft, and also I have obtained an outer portion which is relatively soft to provide a maximum frictional surface for engagement with a belt or other power transmitting device. 125

Furthermore, it is to be understood that the particular forms of apparatus shown and 130 described, and the particular procedure set

forth, are presented for purposes of explanation and illustration and that various modifications of said apparatus and procedure can be made without departing from my invention as defined in the appended claims,—

What I claim as my invention is—

1. A laminated pulley for power transmission comprising a pair of opposed end plates, fibrous laminæ of compressible material of substantially the same internal diameter as the pulley and adapted to form the outer working face of the pulley, a plurality of non-circular, multi-sided plates of relatively hard material of materially less external diameter than the end plates uniformly distributed through the body of the pulley between the fibrous laminæ and concentrically arranged relative to said laminæ, said plates having rivet apertures formed 20 therein aligned with corresponding apertures formed in the fibrous laminæ, each aperture of said plates being arranged symmetrically with respect to the sides of the polygonal plates, and rivet bars extending 25 through the pulley body adapted to fit said apertures to hold the end plates, the fibrous laminæ, and the plates of hard material in rigid assembled relation to form a pulley having a relatively dense internal 30 hub surface formed by said laminæ and said plates of hard material and a relatively soft exterior working surface formed by the laminæ.

2. The invention specified in claim 1 in which the rivets are shouldered adjacent each of their ends and provided with reduced extensions to engage apertures formed in each of said end plates, whereby when said rivet heads are spread each of said end plates will be held rigidly against movement relative to said rivets and laminæ.

3. A pulley comprising a plurality of apertured, circular laminæ of relatively soft material and a plurality of similarly apertured, polygonal, metal plates interposed between said laminæ, end plates on said pulley and rivets passing through the apertures in said laminæ and plates to hold them together, the fibrous laminæ between said plates being substantially compressed, whereby a pulley having a relatively dense interior and a relatively soft exterior is produced.

4. A laminated pulley in which the laminæ are compressed together to form a comparatively hard and dense interior for engagement with the shaft or other support and a relatively loose and softer exterior for frictional engagement with the belt, said laminæ being formed by layers of fibrous material alternating with metal plates, said metal plates being polygonal in form, with slots in the metal plates, each slot extending parallel with the adjacent edge of the metal plate, and rivet bars extending through said

slots and through the fibrous layers compressed between the metal plates, together with end plates held in place by said rivet bars.

5. A structure as specified in claim 4, 70 said end plates being dished to form countersunk ends for the pulley.

6. A structure as specified in claim 4, 75 said metal plates being each octagonal in form.

7. A pulley having a laminated interior formation adapted for direct engagement of the laminæ with the shaft or other support upon which the pulley is adapted to be directly mounted, the laminæ of said interior 80 formation comprising metal plates which are octagonal in form, with slots in said plates, each slot being parallel with the edges of the plate, and rivet bars inserted through said slots to bind the laminæ together. 85

8. A pulley for power transmission comprising fibrous laminæ of compressible material, end plates of substantially the same internal diameter as said laminæ and having 90 inwardly extending cup-shaped portions of less diameter than the outer diameter of said fibrous laminæ, and rivets for holding said end plates against relative movement axially of the pulley, whereby said fibrous laminæ 95 when compressed will have a relatively dense inner portion that constitutes the hub of the pulley and a relatively soft, frictional outer portion.

9. A structure as specified in claim 7, in 100 combination with dished end plates held in place by said rivet bars and forming countersunk ends for the pulley.

10. A pulley comprising a plurality of apertured, circular laminæ of relatively soft material and a plurality of similarly apertured, polygonal, metal plates interposed between said laminæ, end plates on said pulley, rivets passing through the apertures in said laminæ and plates to hold them together, the fibrous laminæ between said plates being substantially compressed, whereby a pulley having a relatively dense interior and a relatively soft exterior is produced, and means mounted on said rivets for clamping the pulley to the power transmitting shaft. 110 115

11. A pulley having a body formed of laminæ of fibrous material side by side, end plates of relatively thin pressed sheet metal having inwardly offset inner portions, and shouldered rivet bars extending through the laminæ and secured to the inwardly offset portions of the end plates whereby the riveted heads of said bars are disposed entirely within and protected by the inwardly offset portions of said end plates, said end plates being spaced by the shouldered portions of said rivets. 120 125
